DESIGN FOR A PHONOGRAPH CABINET

David C. Rockola, Chicago, Ill., assignor, by mesne assignments, to Rock-Ola Manufacturing Corporation, Chicago, Ill., a corporation of Delaware

Application November 13, 1945, Serial No. 123,705

Term of patent 14 years

(Cl. D56—4)

To all whom it may concern:

Be it known that I, David C. Rockola, a citizen of the United States and a resident of Chicago, in the county of Cook and State of Illinois, have invented a new, original, and ornamental Design for a Phonograph Cabinet, of which the following is a specification, reference being had to the accompanying drawing, forming a part thereof.

The drawing shows a perspective view of a phonograph cabinet embodying my novel design, the back of the cabinet being plain and the side wall not shown being identical to the opposite side wall shown in the drawing. The front and rear wall of the cabinet are parallel.

I claim:

The ornamental design for a phonograph cabinet, substantially as shown and described.

DAVID C. ROCKOLA.
